Design No. 675
Jacob De Haas
Design of Bracket

Dated 31 October 1922

Des. 675

Isaac De Gouche Troy. N.York

Letters Patent 675. Dated Oct 31 1854

The Schedule referred to in these Letters Patent and making
part of the same

To all whom it may concern
Be it known that I Isaac De Gouche of Troy in the county

J

Dec

675

of Rensselaer and state of New York have invented or produced a new and original Design of Bracket and I do hereby declare that the following is a full clear and exact description of the same reference being had to the annexed drawing and the letters of reference marked thereon making a part of this specification

My design of Bracket consists of a front plate A and two side plates B. B. (one being a duplicate of the other is not shown in the drawing) The front plate is decorated with the leaf C. on its upper part the stem of which runs down to and terminates at the bottom of the plate in a leaf D. The side plate is ornamented on the edge with a cove moulding (a) terminating at the lower end in the scroll E and at the upper end in the leaves F scroll G and return scroll H.

Having thus described my design of bracket. What I claim as new therein and desire to secure by Letters Patents is: The ornamental configuration and design of bracket such as herein described and shown in the annexed drawing.
